FINISHING MACHINE

John L. Jones, Weymouth, Mass., assignor to
United Shoe Machinery Corporation, Paterson, N. J., a Corporation of New Jersey

Application May 9, 1930. Serial No. 451,159

16 Claims. (Cl. 12—77)

This invention relates to finishing machines and finishing-tool heaters and is herein illustrated as embodied in a machine for operating on shoe bottoms and the sole and heel edges of shoes.

The finishing of soles of shoes requires the use of various scouring, polishing and burnishing tools which are commonly mounted on a single rotating shaft, the various tools frequently being used in succession by one operator, only one tool of a plurality on a shaft generally being used at any one time. It is common in the art to provide in finishing machines of the kind referred to a means for heating the burnishing tool or tools; but since the burnishing tools are not used continuously as above pointed out, it is desirable therefore that the heating means may be easily rendered operative or inoperative according to whether the burnishing tool is being used or not, and also that it shall be capable of heating the tool to the proper temperature quickly.

In view of the foregoing, the invention in one aspect provides in a finishing machine having a moving tool, such, for example, as a rotary burnishing tool, means for heating the tool by frictional engagement with the tool, means for retracting the heating means from the tool, and yielding means arranged alternatively to urge the heating means against the tool and to cause the retracting means to hold the heating means in retracted position. The heating means herein illustrated comprises a friction shoe, and the means herein described for retracting and holding the shoe retracted from the tool consists of a lever and connections between the lever and the shoe comprising a link, the lever being movable to carry the axis of the link toward and beyond the pivotal axis of the lever. The movement of the lever in this direction is limited by a stop positioned to be engaged by the link after its axis has crossed the pivotal axis of the lever. By the use of this mechanism the spring alternatively urges the heating means toward and against the tool when it is desired to heat the tool also holds the link against the stop when it is desired to retain the heating means in inoperative or retracted position.

Invention is also to be recognized in a heater adapted for heating a moving tool comprising a friction shoe arranged for contact with the tool, a support for the shoe, together with means carried by the support for moving the shoe toward the support and yielding means arranged

alternatively to urge the shoe away from the support and to cause said shoe moving means to hold the shoe in its proximal position with respect to the support.

These and other features of the invention will appear more fully from the following detailed description when read in connection with the accompanying drawing and will be pointed out in the appended claims.

In the drawing,

Fig. 1 is a view in perspective showing the invention as embodied in a finishing machine;

Fig. 2 is a side elevation of a part of the device shown in Fig. 1; and

Fig. 3 is an enlarged plan view of a fragment of the device shown in Fig. 2.

The improved device is illustrated in Fig. 1 as supported on a tubular frame element 10 on which the legs (not shown) which rotatably support a finishing shaft 12 are clamped in spaced relation. A friction shoe 14, which is illustrated as used for frictionally heating and cleaning a forepart edge burnishing tool 16 on the shaft 12, is slidably supported in a head 18 of a support 20 which is so clamped to the frame element 10 by means of bolts 22 as to hold the shoe in juxtaposition to the tool. The friction shoe 14 comprises a tool-engaging element 24 which may be of leather or any other suitable material and which is held against a clamp plate 26 having a cylindrical shank 28 by means of another clamp plate 30, the clamp plate 30 and the element 24 being held in assembled relation by means of a bolt 32. The friction shoe 14, the shank 28 of which is slidably received in a recess 34 in the head 18 of the support, is yieldingly urged away from the support and toward the tool 16 by means of a spring 36 encased in the central portion of the shank 28. The stress in the spring 36, and hence the force with which the friction shoe 14 is urged toward the burnishing tool, may be adjusted by means of a set-screw 38 having on its inner end a shoulder 40 arranged to abut the adjacent end of the spring 36 and a reduced portion 42 arranged to extend within the coils of the spring thereby to align the spring and the screw 38. A lock nut 44 on the screw 38 is arranged to secure it in any desired position of adjustment.

In order to enable an operator of a finishing machine in which the invention is embodied to move the friction shoe toward the support and hence to retract the friction shoe from the tool, the illustrated device is provided with a lever 46 pivoted to the head 18 of the support on a

screw 48 which is threaded into a boss 50 extending laterally from the head 18. The lever 46 is in effect a bell crank and is pivoted to a link 52 by means of a pin 54, the other end of the link 52 being also pivoted to the clamp plate 26 of the friction shoe by means of a stud 56 passing through the clamp plates 26 and 30. It will be noted from Figs. 1 and 2 that the link 52 is so bent that its axis, that is, an imaginary line 10 between its pivot points, will move toward and cross the pivotal axis of the bell crank lever 46 when the lever is rotated in a counterclockwise direction from its position shown in Fig. 1 to that shown in Fig. 2. Until the axis of the link, moved 15 as above described, crosses the pivotal axis of the bell crank lever 46, it is apparent that the operator must do work against the spring 36 and that as soon as the axis of the link has passed the pivotal axis of the bell crank lever 46 the spring 20 itself tends to rotate the bell crank lever in the same direction and to urge the friction shoe toward the tool. This latter movement is limited by the link 52 the crooked portion of which is arranged to engage the upper part of the 25 boss 50 which thereby provides a stop which, in conjunction with the link 52, lever 46 and spring 36, holds the friction shoe in retracted position, or in its proximal position with respect to the support 20 as illustrated in Fig. 2.

30 As used in a finishing machine of the type referred to, the device is normally held in retracted position as above described, but when it is desired to use the burnishing tool 16 the operator merely turns the bell crank lever 46 in a clockwise direction, when looking at the machine as indicated by Fig. 2, thereby allowing the spring 36 to urge the friction shoe against the tool. As herein illustrated, the tool-engaging element 24 of the friction shoe engages a substantial extent of both the circumference and width of the work-engaging face of the tool, and accordingly is arranged effectively and expeditiously both to heat and clean the tool. If it is desired to retract the heating and cleaning element from the tool 45 after the completion of a burnishing operation, this may be done by turning the lever 46 in a counterclockwise direction until the link 52 abuts the stop 50 as above described.

50 While the illustrated cleaning and heating means is described as adapted for use with a tool for treating the forepart portion of a sole edge, it is to be understood that the present embodiment of the invention is not limited to use in connection with burnishing tools having work-engaging surfaces adapted for operating on any 55 particular portion of a sole edge or shoe part.

Having thus described my invention, what I claim as new and desire to secure by Letters Patent of the United States is:

60 1. In a finishing machine having a moving burnishing tool, a support, means for heating the tool mounted on said support for movement toward and away from said tool, means mounted to swing on said support for retracting the heating means from the tool, and yielding means arranged alternatively to urge the heating means against the tool and to cause the retracting means to hold the heating means in retracted position.

65 2. In a finishing machine having a moving burnishing tool, means for heating the tool mounted for sliding movement toward and away therefrom, means for yieldingly holding the heating means against the tool, and means for operating said heating means having a limited movement in one direction, said yielding means

being arranged also to hold the said operating means in the extreme position of its limited movement.

3. A heater comprising a friction shoe adapted for engagement with a moving tool, a support for said shoe, means carried by the support for moving said friction shoe toward the support, and yielding means arranged alternatively to urge the shoe away from the support and to cause said shoe moving means to hold the shoe in its proximal position with respect to the support. 80 85

4. A heater comprising a shoe adapted for frictional engagement with a moving tool, a support for said shoe, the latter being arranged to slide in the support, yielding means tending to cause said shoe to move in one direction with respect to the support, and means for moving said shoe in the opposite direction comprising a lever having limited movement and connections between the lever and shoe cooperating with said yielding means to hold the lever at one extreme of its movement. 90 95

5. A heater comprising a support, a friction shoe carried by said support and mounted for movement with respect thereto, means for operating said shoe comprising a lever and link, and a spring arranged alternatively to urge the shoe away from the support and to cause the lever and link to hold the shoe in its proximal position with respect to the support. 100 105

6. A heater comprising a support, a friction shoe carried by said support and mounted for movement with respect thereto, means for operating said shoe comprising a lever having limited movement in one direction, and a spring acting upon said shoe and arranged to hold said lever in the extreme position of its limited movement. 110

7. In a finishing machine having a moving burnishing tool, means for heating the tool adapted for frictional engagement therewith and mounted for movement toward and from the tool, yielding means arranged to urge the heating means toward the tool, and means for retracting the heating means from the tool comprising a lever having limited movement and a member connecting said lever and heating means utilizing said yielding means to hold the lever at one extreme of its movement. 115 120

8. In a finishing machine having a moving burnishing tool, means for heating the tool by frictional engagement with said tool, means for urging the heating means toward said tool, and mechanism comprising a lever and a link for retracting the heating means from the tool constructed and arranged to cause said second-mentioned means to hold the heating means in retracted position. 125 130

9. In a finishing machine having a moving burnishing tool, means for heating and cleaning the tool by frictional engagement therewith, a support for holding said means in juxtaposition to the tool, resilient means in said support for urging the first-mentioned means toward said tool, and means for retracting the first-mentioned means from the tool against the pressure of said resilient means. 135 140

10. In a finishing machine having a moving burnishing tool, heating and cleaning means arranged for movement toward and away from the tool, means for moving the heating and cleaning means between its operative and inoperative positions, and means constructed and arranged alternatively to urge said heating and cleaning 145 150

- means against said tool and to cause said moving means to hold them apart.
11. In a finishing machine having a rotary burnishing tool, means for heating and cleaning the tool by frictional engagement with the periphery thereof, a support for holding said means in juxtaposition to the work-engaging portion of the tool, resilient means for urging the heating and cleaning means toward said tool, and connections for retracting said heating and cleaning means by overcoming the resistance of said resilient means. 80
12. In a finishing machine having a rotary burnishing tool, means for heating the tool by frictional contact with the work-engaging face thereof, a support for holding said means in juxtaposition to the tool, resilient means connecting said support and heating means for urging the latter toward said tool, and connections between said heating means and support for retracting the heating means from the tool constructed and arranged to cause said resilient means to hold said heating means in retracted position. 85
13. In a finishing machine having a burnishing tool, a friction shoe adapted for contact with the tool for heating it, yielding means for urging the heating means toward the tool, means for retracting the heating means from the tool comprising a lever and connections between said lever and said heating means constructed and arranged to utilize the yielding means to hold the heating means in retracted position. 90
14. In a finishing machine having a rotating burnishing tool, a friction shoe adapted for engagement with the work-engaging face of the tool, a support for said shoe, resilient means for urging said shoe against the tool thereby causing the tool to be heated and cleaned, a lever pivoted to said support, and a link connecting said lever and said shoe, said link and lever being constructed and arranged to retract the shoe from the tool and to cause the resilient means to hold the shoe in retracted position. 95
15. In a finishing machine having a rotating burnishing tool, a friction shoe spring-pressed toward said tool, a pivotally mounted lever for retracting the shoe from the tool against the spring pressure, a link connecting said lever and shoe, said lever being movable to carry the axis of the link toward and beyond the pivotal axis of said lever as the shoe is retracted from the tool, and a stop for limiting the movement of the link after its axis has crossed said pivotal axis. 100
16. In a finishing machine having a rotating burnishing tool, a friction shoe adapted for movement toward and away from the tool, a pivotally mounted lever, a connecting link pivoted at its ends to said lever and friction shoe respectively, said lever being movable about its pivotal axis from a position in which the line between the pivot points of the link is at one side of said axis to a position in which said line is at the other side of the pivotal axis, and a stop positioned to be engaged by said link when said line between its pivot point has crossed said pivotal axis. 105
